UNITED STATES PATENT OFFICE.

WALTER KELLNER, OF BARMEN-WICHLINGHAUSEN, GERMANY.

PAPER-TUBE-ROLLING MACHINE.

1,106,714.

Specification of Letters Patent. Patented Aug. 11, 1914.

Application filed May 25, 1911. Serial No. 629,444.

To all whom it may concern:

Be it known that I, WALTER KELLNER, manufacturer, residing at Wiescherstrasse 13, Barmen-Wichlinghausen, Rhenish Prussia, Germany, a subject of the Emperor of Germany, have invented new and useful Improvements in Paper-Tube-Rolling Machines, of which the following is a specification.

10 My invention relates to an improved machine by which paper tubes are rolled and pasted, and it consists in the combination of means by which the blank is cut off from a roll, then adjusted in an exact position, 15 then seized by a nipper and inserted axially in a slot forming roller whereby it is rolled up, and during this operation glue is fed by a brush to the tube, another brush smoothing its surface and a finished tube being then 20 pushed out of the machine.

With these and other objects in view my machine is illustrated on the accompanying drawings and described in the following specification.

25 Figure 1 is a top view of the complete machine with the glue applying rollers 11 removed. Fig. 2 is a front elevation of the complete machine. Fig. 3 is a cross section taken in the direction of line 1—1 of Fig. 30 1 on an enlarged scale. Fig. 4 is a top view of a part of Fig. 1 on an enlarged scale. Fig. 5 is a detail view in elevation of the paper clamp and the tube remover. Fig. 6 is a vertical section on the line 4—4, of 35 Fig. 1. Fig. 7 is a vertical section taken on line 2—2 of Fig. 1. Fig. 8 is a vertical section taken on line 3—3 of Fig. 1. Fig. 9 discloses a view of the gears 41 and 42, and Fig. 10 discloses an end elevation of the 40 forming roller.

Like letters of reference indicate like parts in the drawings.

On the bed plate *a* of the machine is journaled a shaft 1, rotated by the pulley 4 45 which may be driven and arranged to transmit power in any proper known manner, the rotation of shaft 1 transmitting motion by means of the bevel gear 2 to a shaft 3, which by means of the gears 6, 7, 7', 7^a, 7^b, 8 and 8' 50 rotates the rollers 9, between which is guided the paper 10, having previously passed over a glue feeding device 11 of known construction. It follows that the paper then passes between another pair of rollers 12 which 55 guide the paper in to the cutting device 13, said device consisting of two knives, one of

which is alternately raised and lowered by means of a cam 14 keyed to shaft 3. The paper is first clamped down on the table of the machine by the bearing surface 18 of a 60 lever 17 which is operated upon by a cam 16 of shaft 3 and a blank of the desired length is cut from the paper by the said knives 13. On the table is arranged the slide 19 which is secured to a bar 21, which is in engagement with a cam 20 of shaft 3, said slide in operation, shifts the blank laterally with its longitudinal edge against a rigid member 22, thereby securing its proper position relative to the forming roller 24 onto which the 70 blank will be delivered. This work is mechanically carried out by means of a scissors-like tool or nipper 23, said nipper consisting of a member 25 and a coöperating member 26 shown by Fig. 5, and is reciprocated by means of the link 27, levers 28 and 29, crank 29', disk 30, gear wheels 31' and 31, and shaft 1, the said member having a bearing 25' which slides along a shaft 25^a. The members 25 and 26 which are closed by 80 a spring 32 are opened by means of a lever 33 which engages the projection 34 of the nipper, when the latter is in its farthest leftward position. The lever 33 is actuated by a cam disk 35 seated on shaft 1. The nipper members 25 and 26 are held in the open position by a spring actuated arm 36 until they seize the blank engaging for this purpose a protuberance 37 on the projection 34, as shown in Fig. 5. In the right moment, the 85 nipper having received the blank between its jaws, the arm 36 will be released by moving into contact with a rigid bolt 38, and the blank is clamped by said nippers, and can now be inserted thereby into the longitudinal slot 24' of the forming roller 24, which is rotated intermittently, so that the slot will aline with an edge of the paper and guide-bar, for receiving the paper. For this purpose the rotation of said shaft is 90 momentarily interrupted which is effected by means of ordinary quadrant gear 39 mounted on shaft 3, which is in mesh with the gear train 40, 41 and 42, which is arranged for increasing the angular velocity 95 of the forming roller 24. Journaled in suitable bearings is a shaft 43 which is revolved from shaft 3 by means of gears 44, 45, 46, which shaft is fitted with two brushes 47 and 48. The shaft 49 is provided with a spoon-like plate 50 that is rocked by a cam 51 of shaft 3, which plate takes glue from a re- 100

ceptacle 52, applies said glue to the brushes 47 and 48, which apply the glue on to the blank. The superfluous fluid will be removed by a sheet metal plate 53, carried by 5 two arms 54 which are pivotally mounted on shaft 49, and are caused to oscillate by means of a roller 55 and the cam 56 on shaft 3, the roller 55 being carried by a shaft 55' journaled in the arms 54. It will be understood 10 that in this manner the glue is removed and also the paper of the roll is pressed down and made smooth, for which latter purpose the brush is also of effective use. After the paper tube has been finished 15 it is turned out of the machine by the following means: On the said forming roller 24 is mounted slidably an expeller 57 which is within the path of two rings 58 and 59, which are slidably mounted on a shaft 5. 20 To said rings is fixed a cable 62, which is guided over the rollers 60 and 61 and has its ends connected with the member 25, so that it is shifted to and fro as the nipper moves, being thus reciprocated forward as the nipper moves backward, and vice versa. By 25 this means the expeller will be moved along the forming roller 24 and cause the tube to be thrown from the roller out of the machine.

What I claim is:

1. The combination in a paper tube machine, of a bed plate, a table over the bed plate, a guide bar on the table, means for causing a strip of paper to move forward

over said table, means for applying glue to 35 one surface of said paper as it moves forward toward the table, means for clamping the paper on the table, means for cutting off a blank from said paper while it is clamped on the table, means for shifting the 40 blank laterally until an edge thereof comes into contact with the guide bar, a slotted forming roller, means for rotating the roller intermittently so that it stops with its slot in alinement with an edge of the guide bar 45 and of the paper, and means for moving the blank forward with an edge thereof in said groove, said roller winding said blank thereon as it rotates, and means for applying glue to the other surface of the paper blank 50 while being wound.

2. The combination in a paper tube machine, of means for cutting a blank from a strip of paper, means for applying glue to said strip before said blank has been cut, a 55 roller having a groove therein, a guide bar, means for shifting the blank laterally with one edge against said guide bar, means for rotating said roller intermittently so that the groove thereof stops in alinement with 60 said edge of the blank, means for grasping said blank and drawing said edge into said slot, whereupon the rotation of said roller winds the blank thereupon.

WALTER KELLNER. [L.S.]
